TYPEWRITING MACHINE

William F. Helmond, West Hartford, Conn., assignor to Underwood Elliott Fisher Company, New York, N. Y., a corporation of Delaware

Application November 28, 1934, Serial No. 755,110

2 Claims. (Cl. 197—103)

This invention relates to the finger-struck key-heads of a typewriter-keyboard or the like; and provides a finger-cushioning key-head constructed, and mounted on its key-stem or key-lever, 5 so as to be capable of yielding universally when engaged by the finger, thereby to gain a finger-cushioning effect which conduces greatly to ease of operating the keyboard.

The invention further aims to provide the 10 novel key-head in a durable and compact form which may be manufactured inexpensively, may be attached inexpensively, securely and neatly, to the key-lever; and, further, so that the novel key-head, even though its finger-cushioning quality is 15 greatly increased, need not be of greater overall diameter, or may even be of less diameter, than the regular rigid key-head, in order to minimize the liability of striking two keys simultaneously.

The novel key-head is made preferably of soft 20 cushioning rubber.

In order that the finger-struck top portion of the key-head may yield universally, that is, be capable of yielding locally for the requisite cushioning effect at whatever part of its top surface 25 it is struck by the finger, and moreover be capable of yielding in directions transverse to the vertical, so that transverse components of finger strokes are also effectively cushioned, said top portion is of shallow depth and surmounts a reduced neck that is also shallow, and preferably 30 hollow by reason of being made of annular form.

Fastening means for securing the novel key-head to the head-receiving seat of the rigid key-shank engage the key-head only at a base-portion 35 which is also shallow and is surmounted by said neck, so that the finger-struck top portion of the key-head is spaced from said fastening means. Said shallow neck thus acts as a resilient, universally yieldable support for the finger-struck 40 top portion of the key-head to conduce to the finger-cushioning quality of said top portion.

The hollow neck is reduced, that is, made 45 smaller in outer diameter than the finger-struck top portion of the key-head, to the further end that the edge or rim of said shallow top portion is in the form of an outwardly-extending flange or lip, and is therefore free to yield and flex locally of itself to conduce to the cushioning of the finger stroke.

50 Since the hollow neck is itself resiliently compressible, it will yield to permit, and conform to, whatever vertical localized yielding and resultant flexing of the button-like top portion of the key-head take place to cushion the finger impact.

55 The reduced hollow neck is also sufficiently

tractable to yield transversely, to permit, and conform to, whatever transverse yielding of the top portion of the key-head is necessary to cushion the finger stroke.

The central section of the top portion of the 5 key-head which overlies the recess formed by the annular neck may be limited in thickness, by reason of said recess, in order to yield of itself to conduce to the finger-cushioning quality of the novel head, said recess also rendering the 10 shallow neck hollow inasmuch as it may extend from the bottom of the base-portion.

For attaching and securing the novel head to the rigid key-shank, the base-portion, separated from the top portion by the neck may be enlarged relatively to said neck to afford an outer flange or shoulder against the top of which suitable fastening means may be drawn to secure the key-head to the rigid key-shank; said fastening means engaging only said base-portion, in order 20 to leave the top portion of the key-head free to yield universally. Said key-shank is provided with a seat against which the base-portion is drawn by said fastening means. Said fastening means may be arranged so as not to interfere 25 with the described universal yielding of the finger-struck top portion of the key-head and the underlying reduced hollow neck.

Other features and advantages will herein-after appear.

30 In the accompanying drawing,

Figure 1 is a side view showing the novel key-head and the manner of mounting and securing same to the key-lever.

Figure 2 is a side view showing the key-head, 35 its seat on the key-shank, and the fastening means in section. The view also illustrates how the key-head yields not only downwardly, but also transversely, to effectively cushion the finger when the latter strikes the key-head eccentrically.

Figure 3 is a front view of the key-lever and novel key-head; the seat and fastening means being shown in section to illustrate details.

Figure 4 is a section view showing the novel 45 key-head as being formed with a concave finger surface.

Figure 5 is a view illustrating the manner in which the top portion of the head and the underlying pad-like reduced neck yield to cushion the 50 finger when the latter strikes at about the middle of the key-head.

Figure 6 is a view of the forward part of the key-lever showing the same and the novel key-head and fastening means in perspective.

A partly-shown key-lever 1 has a key-shank 2 provided with a plate 3 upon which the novel finger-cushioning key-head 4 is seated and retained.

5 The key-head-seating plate 3 has a tubular trunk 5 into which the upper end 6 of the key-shank 2 may be forcibly driven, for permanently securing said plate 3 to the key-lever 1.

The finger-cushioning key-head 4 is preferably 10 made of soft rubber, and includes a disk-like, that is, shallow button-like, top portion 7, the top surface of which is struck by the finger.

In order to gain universal yieldability of the finger-struck top portion 7, and thereby improve 15 the finger-cushioning quality of the key-head 4, said top portion 7 surmounts a neck 8. The bottom of said key-head rests directly upon the key-head-mounting plate 3, and means for fastening the key-head to the key-lever 1 are arranged to 20 engage said key-head only at the base of said key-head neck 8, in order that said neck 8 may yield universally to conduce to said universal yieldability of the finger-struck top portion 7.

To provide for such fastening of the key-head, 25 the base-portion of the key-head may be enlarged outwardly from the neck 8 to form a flange which affords a shoulder 9 to which key-head-fastening means may be applied. Said shouldered base-portion fits within an upturned edge 30 portion or rim 10 of the key-head-mounting plate 3, said rim 10 thus co-operating to retain the key-head transversely upon key-seating plate 3.

The outer periphery of said upturned plate- 35 rim 10 may also centralize a surrounding, preferably separate, key-head-fastening ferrule or ring 11. Said ring 11 is turned inwardly at its top, as at 12, to overtop the key-head shoulder 9 for retaining the key-head upon the plate 3, and to 40 this end said ring 11 is also turned inwardly at its bottom, as at 13, to react against the under side of the edge of the plate 3.

The neck 8 is made of annular section for the purpose of enabling it to yield readily, and therefore 45 by conduce to the universal yieldability of the finger-struck top portion 7. Furthermore, making the neck 8 of annular section also forms a recess 14 under the central section 15 of the finger-struck top portion 7, so that said central 50 section is of sufficient thinness to conduce to the finger-cushioning yieldability locally of said top portion 7.

To further conduce to the universal yieldability of the finger-struck top portion 7, the underlying neck 8 is of smaller outer diameter than said top portion 7, thereby forming a free and therefore readily yieldable outer rim section or lip 16 for said top portion.

The neck 7 extends above the shoulder 9 far 60 enough to separate the under side 17 of said free lip 16 of the top portion from the top 12 of the fastening ferrule 11 by a space 18, Figures 4 and 3, said space 18 being sufficient to permit adequate downward yielding of said free lip or flange 65 16.

Figure 2 illustrates how the key-head may yield, by reason of its novel construction and mounting, to effectively cushion a finger stroke that impacts eccentrically upon the key-head and 70 has a forward component at the time of impact. Under such eccentric and forwardly tending impact, the neck 8 will be compressed locally and in varying degree to permit, and conform to, the finger-cushioning yielding and resultant flexing 75 of the top portion which take place substantially

as shown in said Figure 2. The compressed portion of the neck 8 will also yield forwardly, mostly at its upper unfastened part above the ring 11, 12, to permit and conform to forward yielding of the top portion 7 which may take place substantially as shown to cushion the forward component of the finger impact; it being noted that in Figure 2 the dotted outline 7a indicates the key-head in its initial unflexed condition, that is, before it is struck by the finger.

Figure 5 illustrates the novel key-head as yielding in a way different from that of Figure 2 to cushion a finger stroke that strikes the key-head substantially squarely at about the middle of its top. In such case the annular neck 8 will be compressed, substantially uniformly all around, and will be flexed somewhat inwardly at the top to permit, and conform to, the finger-cushioning yielding and resultant flexing of the top portion 7 which take place substantially as shown in Figure 20 5, in which the dotted outline 7a indicates the normal condition of the key-head.

It will be seen that the capability for free and varying yielding and flexing of the top portion 7 as exemplified by Figures 2 and 5, and the resultant improved cushioning quality of the key-head are gained by the use of the described combination of features, inasmuch as such use enables the disk-like top portion 7 to yield locally, and to substantially equal degree, over substantially its 30 entire area; and, moreover, enables said top portion 7 to yield transversely. The recess at 14 may be concave at the top, to conduce to yieldability of the top portion 7. It will be evident that the improved key-head is compact vertically 35 and need be of no greater diameter than the regular rigid key-head, and may even be of less diameter, in order to minimize the liability of striking two keys of the keyboard simultaneously.

The key-head may be inexpensively molded 40 from soft rubber. The appropriate key-character 19 may be marked in any suitable way upon the top finger surface of the key-head.

In the preferred and illustrated form of the key-head-retaining ring 11, the inwardly-turned 45 top portion 12 of the latter is in the form of an inwardly-turned flange extending all around the ring. The key-head, being of soft rubber, may be compressed to pass the shoulder-forming enlargement at the base of the key-head through the central opening afforded by said inwardly-turned flange 12 of the ring. The inwardly-turned bottom portion 13 of the key-head-fastening ring 11 is preferably in the form of individual prongs, as indicated in Figure 6 at 13a. Said prongs 13a are 55 initially straight, that is, they extend directly downward from the ring-portion 11.

In assembling the parts, the soft rubber key-head is first inserted into the ring 11, 12, and the key-head and its said ring 11, 12 are then placed 60 upon the key-plate 3, with the ring 11 encircling the upturned rim 10 of said plate. The prongs 13a of the ring are then bent inwardly against the under side of the edge of the plate 3 in such manner as to enable the ring 11, 12 to keep the bottom 65 of the key-head against the top surface of the seat or plate 3 as indicated.

The top finger-surface of the key-head may be flat as indicated in Figures 1, 2, 3, 5 and 6, or it may be made concave as indicated at 7b, Figure 4. 70

It will be seen that the novel key-head 4 is compacted vertically by reason of the individual shallowness of each of its constituent elements, namely, the shallow top portion 7, the shallow neck or fillet 8, and the shallow base-portion demarcated 75

5 by the shoulder 9; and that the shallow neck-
portion or fillet 8 is sufficiently compressible and
tractable to conduce to universal yieldability of
said top portion 7. Said neck 8, because of its
shallowness, is in the nature of a fillet, and is
therefore in congruence, for the purpose of the
invention, with the shallow top portion 7 and
shallow base-portion. Because of its compact
proportions, the novel key-head 4 is substantially
10 approximate to the proportions of the conven-
tional rigid typewriter key-head structure, and
therefore fulfills an important desideratum.

Variations may be resorted to within the scope
of the invention and portions of the improvements
15 may be used without others.

Having thus described my invention, I claim:

1. In combination with a typewriter-key stem,
a key cup mounted directly thereon, and retaining
means associated with said key cup; a finger cush-
20 ioning key-head of resilient material comprising
a base member adapted to fit within the confines
of said key cup, an annular recess in said head
above said base, forming a base shoulder and a
shallow neck in the nature of a fillet, said retain-
25 ing means extending into said recess in engage-
ment with said shoulder, a shallow top portion
overlying the recess in spaced relation from said

base to afford a flexible border rim, the diameter
of said top portion being substantially the same as
that of said key cup and retaining means, to pro-
vide a vertically and diametrically compact key-
head.

2. In combination with a typewriter-key stem,
a key cup mounted directly thereon, and retaining
means associated with said key cup; a finger cush-
ioning key-head of resilient material comprising
a base member adapted to fit within the confines 10
of said key cup, an annular recess in said head
above said base, forming a base shoulder and a
shallow neck in the nature of a fillet, said retain-
ing means extending into said recess in engage-
ment with said shoulder, a shallow top portion 15
overlying the recess in spaced relation from said
base to afford a flexible border rim, the diameter
of said top portion being substantially the same
as that of said key cup and retaining means, a
central recess in said key-head extending from 20
the underside of said base portion and through
said neck, to thin the central section of said top
portion, thereby providing a vertically and di-
ametrically compact key-head of universal finger-
cushioning yieldability.
